COMBINATION LOCK

Filed Oct. 18, 1927

UNITED STATES PATENT OFFICE

FRANCIS CARTERET BISHOP, OF CALCUTTA, INDIA

COMBINATION LOCK

Application filed October 18, 1927, Serial No. 226,941, and in British India September 1, 1927.

This invention relates to locks and has for its object to provide a combination lock of the kind which has a number of press knobs, buttons or the like operating and controlling members of which a certain combination must be operated in a suitable manner in order to free the lock and which is so arranged that if other than the right combination is operated the lock will not be freed. The main object of the invention is to provide a combination locking mechanism, so arranged that it will open when the particular combination to which it is set is operated, but which can also be released so that, when desired, the lock may be opened without the necessity of operating the said combination, or, alternatively, without having to operate the whole of the combination. It is an observed fact that combination locks are mechanisms which are most attractive when new or until the novelty wears off, but that after using such a lock for a few weeks the possessor finds it irksome to have to operate the mechanism each time he wishes to open the door or receptacle which the lock fastens. This is more particularly the case when the receptacle is empty or does not contain any objects of value or of a private nature. In such circumstances it is very desirable to dispense with the trouble entailed in operating the combination. The present invention provides such a combination lock which is provided with a latch bar adapted to operate all or part of the locking means thus to avoid the necessity of operating these means in all cases.

With these and other objects in view the invention consists of a combination lock for a box lid, drawer, door or the like of a kind in which a plurality of actuating members such as press buttons or equivalent means are provided all of which may be depressed, pushed in or suitably manipulated in an attempt to release the lock, and in which it is to be operated in order

to permit the lock to disengage to enable the full and proper complement of correct press buttons or the equivalent is not operated, or if any incorrect button or equivalent is operated, the lock will not be disengaged. The invention is further characterized by having a latch bar and connections between said latch bar and each or any of the locking bolts or pieces operable by the said operating means, so that the said latch bar may be operated to throw all or any desired number of the locking bolts or pieces out of operation so as to free or partially free the locking bolts. It also includes a combination lock having a latch bar or releasing means as described above so arranged that the said release may be operated and may then be fixed when desired to hold the locking bolts free. The said combination lock may, when applied to a receptacle and the said receptacle is unlocked and opened, have its latch bar set and fixed to hold the locking bolts in released position so that the said receptacle may be opened or closed without needing to operate the combination. When applied to the securing of a door, such as the door of a house, which may be opened from either side, the combination lock may be operable from one side (the outside) only but the latch bar be operable from the inside of the door. Alternatively, in such a case the latch bar may be operable from both the inside and the outside of the door.

In the latter case the latch bar may be provided with a bolt or catch which can be operated, for example from the inside of the door only, to prevent the latch bar from being operated from the outside to release the locking bolts. The invention further includes a combination lock with a latch bar as described above in which the latch bar is adapted, when moved in one direction, to move all or certain essential of the locking bolts out of locking position, but which when not so moved will tempt to release the lock, and in which it needs certain only of said press buttons or the corresponding press knobs or buttons, so their equivalents to be operated in order that the door may be opened from the outside.

by the proper working of the lock freeing combination mechanism irrespective of whether the latch bar is free or is engaged by a catch or bolt.

- 5 The invention will now be described with reference to the accompanying drawing which shows, by way of illustration only, certain forms which the apparatus may take, which forms are not however to be taken as 10 in any way limitative of the scope of the invention.

In the drawing:

Fig. 1 is a cross section through the lock as applied to a box lid or drawer—the parts 15 being shown with the moving part of the lock in their open position. This figure shows a section through a locking bolt and illustrates the mechanism without the latch bar fitted thereto;

20 Fig. 2 is a similar section to the last but taken through a dummy bolt and its controlling press button;

Fig. 3 is a cross section similar to Fig. 1 of the parts in the completely closed and 25 locked position;

Fig. 4 is a sectional plan on line A A of Fig. 3 showing the normal position of a ten-part combination lock in locked position;

30 Fig. 5 is a diagram showing the said lock when operated in a correct manner to free the same;

Fig. 6 is a similar diagram showing the same lock with the same combination but 35 operated in an improper manner and hence with the locking mechanism still not free;

Fig. 7 is another view in cross-section of the inner or bolt carrying part showing the latch bar (in raised position);

40 Fig. 8 is a similar view with the latch bar in its normal position in which it does not in any way affect the operation. In this case the press knob opposite the section in question is supposed to be depressed;

45 Fig. 9 shows a view of a means for operating the latch bar by turning on operating handle;

Fig. 10 shows a view at right angles to the 50 last in which the latch bar lifting spindle is fitted with a coned cam to enter the proper space therefor; and

Fig. 11 shows a cross section of a combination lock of this general form applied to say 55 the front door of a house.

Referring now to Figs. 1 to 4. The fixed part of the drawer or body of the box is indicated by 1 and the moving part of the drawer or lid of the box by 2. The fixed part 60 1 has an aperture or series of apertures or a suitable groove 3 therein for the lock operating mechanism and the moving part 2 a similar or corresponding aperture, apertures or groove 4 for the corresponding parts of 65 the mechanism.

The groove or the like 3 has a series of press buttons or the equivalents 5 therein.

70 Into these press buttons the short body pieces 6 or the long body pieces 6a may be screwed or otherwise attached. As the apertures 3 or 4 will for convenience be rectangular, or have means to prevent the body pieces rotating therein, it will generally be found convenient to screw the press buttons thereon.

75 When assembled the feathers or ribs 7 prevent the body pieces 6, 6a from being removed from the lock by movement to the right. The caps 8 which may be screwed onto or attached to the press buttons 5 will prevent the said parts being pressed in too far as the inner edges of these caps also then will engage the said feathers, ribs or pierced partition member 7.

80 Incidentally a pierced partition as indicated at 40 in Figure 3 with holes therein closely to fit the press buttons and to act as a guide for the press buttons will be found more convenient than simple ribs 7. Springs 85 41 may normally hold the press buttons in their extended positions.

90 When the press button concerned is one which normally lies opposite to a locking bolt it is fitted to a short body piece 6 and in its normal position the end 9 of such body piece is depressed by a distance x behind the rear face 10 of the part 1.

95 The distance x is the distance each of the parts is adapted to move in operation. It is the distance by which the locking bolt 11 is intended normally to enter the rear part 100 of the aperture or the like 3 in order to lock the parts.

105 In normal conditions when the lid or door is completely closed the ends 12 of the locking bolts 11 enter the apertures or the like 3 in the part 1 by an amount " x ", and lock the parts together until the corresponding press buttons 5 are depressed by the said amount " x " thus freeing the lock.

110 When however the press button is one which lies opposite to a dummy bolt it is fitted with a long body piece 6a the rear end 9a of which normally is practically flush with the rear surface 10. The said long body piece 115 6a is longer than a short body piece 6 by the amount " x ". If then the press button indicated in Fig. 2 with a long body piece 6a is depressed the end of this body piece protrudes beyond the surface 10 as shown dotted in this figure and may enter the corresponding aperture, groove or depression 4 in the part 2 thus preventing the freeing of the lock if and for so long as the said button is depressed.

120 Opposite to each long body piece 6a a dummy bolt 11a is placed. This dummy bolt is shorter than a locking bolt 11 by an amount equal to " x ".

125 In normal conditions the end 12a of the dummy bolt 11a is flush with the surface 13 of the part 2 and when the lid, drawer or the 130

like is in closed position the said end 12a is in intimate contact with the corresponding end 9a of the long body piece under the action of a spring 17.

5 The locking bolts 11 or dummy bolts 11a are provided with screwed stems 14 which screw into hollow sleeves 15.

A rib, feather or, if preferred, a pierced plate 16 prevents the bolts 11 or 11a from being pressed in too far.

The sleeve 15 may have a flange 15a against which one end of the spring 17 presses. The further end of said spring 17 abuts a back plate 18.

15 Referring to Fig. 3 it will be seen that the end of the locking bolt 11 has entered the recess 3 and the lock is not free. The spring 17 is pressing the bolt 11 into the recess 3 and into intimate end contact with the short body piece 6.

Referring now to Fig. 4 it will be seen that a lock having ten parts is shown. The ten press buttons are indicated as letters A to J. Of these the press buttons B, C, E, G, I and J are the correct buttons to push to free the lock as they are opposite to projecting bolts 11, 11, which engage their side of the door. Now, unless all six press buttons are duly pressed and held down the locking will not be freed. The buttons A, D, F and H are opposite to dummy bolts. If any of these four buttons is pressed the end of the long body piece carried by the button will enter the corresponding recess 4 and will prevent the freeing of the lock.

Fig. 5 shows diagrammatically the lock with the proper buttons B, C, E, G, I and J depressed and the bolts are all freed.

Fig. 6 shows diagrammatically the lock with buttons A, C, E, G and H pressed in. It will be seen that locking bolts opposite to B, I and J still engage whilst the long body pieces opposite A and H, which are improper buttons to press, have been made to protrude and also now prevent the freeing of the lock.

On examining the Figures 1 and 2 it will be apparent that the locking bolt 11 and the long body piece 6a may be made of exactly similar construction and be interchangeable. Also the dummy bolt 11a and the short body piece 6 may also be exactly similar and also be interchangeable.

The parts 6, 6a, 11 and 11a are best made rectangular in cross section so that they will not turn in their recesses or grooves 3 or 4. It is desirable that they should not turn because one of the surfaces should be bevelled. In Fig. 1 the lower corner 36 of bolt 11 is bevelled off so that as the part 2 moves down to take up the fully closed position of the box the said bevel 36 shall strike the corner 37 and the part 11 be forced back into its recess 4 against the resistance of its spring 17 to snap out again when it comes opposite

to the recess 3 and to thus secure the lock automatically.

The upper corner 39 of the short body piece 6 is similarly bevelled so that if by any chance the end of this piece projected out from the inner surface 10 of the part 1 it would be forced back by contact with the corner 38. Only a slight bevel of the corner 39 is however needed as from its construction it cannot project to any extent.

In a similar manner and for analogous purposes the corners of 11a and 6a are bevelled.

In assembling—assuming that the parts 11, 11a, 6, 6a are square or rectangular in section, they are placed in their appropriate recesses and the sleeves 15 or the press button shanks 5 are screwed on. To facilitate this the back ends of the sleeves 15 and the front ends of the parts 5 may have a slot for a screw driver made therein.

These parts 15 and 5 may conveniently be cylindrical in shape and closely fit the holes in the ribs or partitions 16 and 7 respectively.

The front ends of the parts 5 may be covered by press button caps 8 screwed on. These caps prevent the press buttons being pressed right through into the interior of the box. If desired springs 41 (see Fig. 3) may be introduced between the parts 7 and the inner edges 8a of these caps to hold the press buttons in desired positions.

To alter the combination the back plate 18 is unscrewed, the springs 17 taken out and the sleeves 15 unscrewed thus liberating the parts 11 or 11a. At the same time the caps 8 may be unscrewed and the press buttons 5 then unscrewed from the parts 6 or 6a. Any proper rearrangement of the elements may then be made.

Figs. 7 and 11 show the essential features of the invention comprising the combination of locking means together with releasing means, such as a latch bar, and connecting means between the releasing means and the locking means so adapted that the releasing means may be operated to release any desired portion of the locking means without the necessity of having to operate the said locking means individually.

Fig. 7 shows the invention applied to a door and in which the latch-bar 19 is illustrated. A headed screw 20 screws into the sleeve 15 and its head 21 engages the said latch bar. If then the latch bar 19 is raised—i. e. moved away from contact with the back plate 18—it will draw all the locking bolts 11 or dummy bolts 11a back with it against the compression of their springs 17, 17 and will free the engagement thereof with the other side of the lock.

To conveniently raise the latch bar 19 a spindle 22 may be provided having a suitable bearing or foot-step 23 and an operating head 130

24. A worm or bevelled surface 25 on the spindle 22 engages the latch bar 19 and on being rotated raises it as shown in Fig. 7.

It will be observed that the back plate 18 and the latch bar are both pierced for the passage therethrough of the shank of the screw 20. As indicated in Fig. 8 the locking mechanism may be freed by operating the proper push buttons without affecting the latch bar 19.

Figs. 9 and 10 indicate one manner in which a latch operating handle may be fitted which, passing through a door, may be used to lift the latch bar from the outside of the door.

15 In this arrangement the back plate 18 is depressed or has a recess 26 formed therein opposite the latch operating spindle. The latch bar 19 is raised or kinked at this point, for example as indicated at 27. The latch 23 operating spindle 28 has an eccentric part or a cam 29 fitted to its inner end and the inner surfaces of the depressions 26 and 27 are so formed that the said eccentric projection when the latch bar is not raised normally will 25 lie in the depression formed by depression 26 whilst when the spindle 28 is rotated the cam surfaces will coat with the inner surface of part 27 to cause the latch bar to rise.

To normally hold the spindle 28 with its 32 projection 29 in such a position that the latch bar is not raised the handle 31 may be a heavy handle so fixed and balanced as to cause the eccentric part automatically to take up the 39 position shown in Figs. 9 and 10 when released.

It is of course necessary to be very sure 46 that the latch spindle and the eccentric 29 shall not become stuck in an improper position and to assist this the eccentric part 29 may be bevelled as indicated at 30 if it is intended to move relatively to the latch bar 19-27.

Fig. 11 shows the combination lock applied 47 to a door. The part carrying the press buttons is in this case fitted to the door jamb 32 and a suitable recess 33 is provided to enable the fingers to be inserted to operate the press buttons.

The rear portion 34 of the lock is in this 52 case suitably formed as a projection from the back or inside of the door in which projection or bracket 36 one half of the locking mechanism and a latch lifting and securing means may be fitted.

55 This latch lifting and securing means is illustrated in Fig. 11 which shows a handle 35 fitted to the inner end of the latch bar lifting spindle 28 (such for example as shown more clearly in Figs. 9 and 10) which when turned in one direction will raise the latch bar 19 for example as in Figures 9 and 10—but which when turned in the other direction will lower the latch bar into the position shown. The knob 35 may be attached to 65 the same spindle 28 as the latch operating

handle 31 and its automatic return to the non-raising position of the latch bar be controlled by the weight of the said handle 31. In such a case a separate bolt or catch 42 may be fitted to, say, the part 34 to prevent the lifting of the latch bar when the inmates of the house 70 wish to make entrance impossible without operating the correct lock freeing combination. Means may be provided whereby some 75 of the bolts are released by the latch bar. This may readily be effected by inserting screws 20 into the bolts which are to be released and omitting these screws in other positions.

The latch bar might thus be utilized to 80 simplify the combination and to throw certain of the bolts out of action thereby enabling the lock to be operated using fewer fingers when the latch bar had been lifted and 85 fixed in lifted position than when the latch bar was not so lifted.

It will of course be understood that the 90 scope of the invention is not by any means limited to the constructional features described or illustrated. No two lock designers 95 would supply similar details, and the scope is intended to include all reasonable modifications. The details of the parts could be altered considerably.

It will of course be understood that the 100 press buttons or the combination operating means may be on either the moving part or on the fixed part of the door or of the door jamb—or either on the body or on the lid of the box or the like and the scope of the invention and the accompanying claim are to be understood to cover all such modifications.

Having now particularly described and 105 ascertained the nature of my said invention and in what manner the same is to be performed, I declare that what I claim is:

In a combination lock, a plurality of locking members, some of which are normally in locking position while the others are normally in open position, all said locking members having spring devices to return them when disengaged to their normal positions, a plurality of operating devices for said locking members, a releasing means to engage said locking members, said releasing means projecting from both sides of the combination lock and means connecting the releasing means to the locking members normally in closing position for releasing said locking members without actuation of said operating devices, and means to return the said locking members automatically to locking position when disengaged by the releasing means.

In testimony whereof I hereto affix my signature this sixteenth day of September, 1927.

FRANCIS CARTERET BISHOP.
